Inland Steel Company, Chicago, Ill., a corporation of
Delaware

Filed Feb. 1, 1967, Ser. No. 613,280

5 Claims. (Cl. 294—81)

ABSTRACT OF THE DISCLOSURE

Disclosed is a device for handling slabs of metal or other material. The device utilizes a pair of spaced apart lazy tongs characterized by elements which permit parallel movement of the tong jaws, and freedom from structural elements which protrude significantly beyond the width of the gripping jaws regardless of the distance at which they are apart. The device permits the stacking of slabs into piles very close together since only a small distance between piles is required for the jaws to satisfactorily grip and lift slabs from a pile.

BACKGROUND OF THE INVENTION

(1) *Field of the invention.*—This invention relates to lifting devices. More particularly, it is concerned with devices used for lifting slabs of material which are more or less rectangular in shape, particularly metal slabs of steel.

(2) *Description of the prior art.*—In the manufacture of steel products it is common for steel ingots to be processed into steel slabs which are subsequently formed into various products such as steel plates and sheet metal strip. Since steel slabs are not normally converted into other products immediately after being formed, they are commonly stored in a slab yard. The steel slabs are generally placed one upon another into consecutive piles located in rows with each pile of slabs spaced apart from the next pile.

The amount of steel which can be stored in a slab yard will be determined to a considerable extent by the space between the slab piles. The closer the slab piles are placed to one another, the greater will be the amount of steel that can be stored in any particular yard at one time.

In the handling of steel slabs to and from a slab yard equipment must be employed that can handle extremely heavy loads, such as up to 125 tons, and handle slabs varying in width from about 1½ feet to over 6 feet. For this purpose, very rugged and strong lifting tongs have been employed in the past. Such lifting tongs have been used in a pair spaced apart by suitable spacers. Such tongs have been crescent shaped in a manner quite similar to the shape of tongs used for manually handling block ice. The arcuate shape of the tongs, plus the protruding linkages used to operate the tongs, made it necessary for the slab piles to be spaced apart from 4 to 6 feet. Closer stacking of the slabs in piles was either impossible or extremely impractical because of the clearance needed for the lifting tongs to properly fit between the piles and grip the slabs to be moved.

SUMMARY OF THE INVENTION

This invention provides a lifting device for slabs of metal, and other heavy materials, which permits stacking of the slabs into piles closely spaced together. The piles can be positioned close together readily using the lifting device of this invention and, furthermore, the lifting device can be used subsequently for removing one or more of the slabs from such closely spaced slab piles.

The lifting device provided by this invention for handling metal slabs and the like comprises a pair of similar gripping members of the lazy tong type connected in parallel spaced apart relationship from each other by rigid

2

spacers, each gripping member having two opposing jaws and jaw actuating means which moves the jaws in and out in parallel relationship to one another, each jaw having a jaw body and an elongated bar extending therefrom, a pair of intersecting lever arms pivotally connected to each other and pivotally connected at each lower end to a jaw body and at each upper end to the lower end of a pair of actuating links with the upper ends of the actuating links being pivotally joined together, guide means pivotally mounted on the gripping member separately receiving each elongated bar through a hole therein, and means operably associated with said actuating links to thereby simultaneously lift both gripping members whereby the weight of the lifting device and any load between the jaws forces the opposing jaws inwardly toward each other.

The lifting device is further characterized in one embodiment by having a rigid spacer joining opposing gripping members at the intersecting pivot of the lever arms, and another spacer joining the opposing gripping members about at the connecting pivot of the upper ends of the actuating links. In addition, the pivot for the guide means, and the pivotal connection of the lever arms with the links are positioned so as to have a common axis. It is also advisable for each lever arm, and each actuating link, to be made of at least two spaced apart bars of rods.

DESCRIPTION OF THE INVENTION IN CONJUNCTION WITH THE ATTACHED DRAWINGS

The invention will now be discussed in conjunction with the attached drawings in which:

FIGURE 1 is an isometric view of one embodiment of the slab lifting device;

FIGURE 2 is a front elevational view of the slab lifting device of FIGURE 1 with the jaws in an open non-lifting position;

FIGURE 3 is a front elevational view, similar to FIGURE 2, but with the jaws in a gripping and lifting position;

FIGURE 4 is a slightly enlarged view showing in greater detail the guide means through which the elongated bar attached to the jaw slides up and down in the guide means during actuation of the lifting device;

FIGURE 5 is a vertical sectional view through the lower center part of a jaw;

FIGURE 6 is an isometric view of the jaw ends;

FIGURE 7 is an elevational view, partly in section through the pivoting means joining the links together;

FIGURE 8 is a plan view of the spacer separating the pairs of lever arms;

FIGURE 9 is a vertical sectional view along the line 9—9 of FIGURE 8; and

FIGURE 10 is a plan view, partially in section, of one end of the spacer which separates the pairs of actuating links.

In discussing the various elements of the drawings the same identifying number will be used for the same part in the various figures so far as is practical.

The lifting device of FIGURES 1 to 3 has a pair of similar gripping members 10 and 11 which are generally described as of the lazy tong or lazy scissors type. The pair of gripping members 10 and 11 are positioned opposite each other in parallel spaced apart relationship but are connected to one another by rigid spacers 12 and 13. Each gripping member has two opposing jaws. The gripping member 10 has opposing jaws 14 and 14A while gripping member 11 has opposing jaws 15 and 15A. The jaws have openings 90 to keep weight down. Each jaw has an elongated bar extending upwardly therefrom. Jaw 14 has rod 16 while jaw 14A has rod 16A; jaw 15 has rod 17 and jaw 15A has rod 17A.

Each gripping member 10 and 11 has a pair of intersecting lever arms pivotally connected to each other inter-

mediate their ends and pivotally connected at each lower end to a jaw body and at each upper end to the lower end of a pair of actuating links. Thus, gripping member 10 has lever arm 18, composed of two rods 18A and 18B, pivotally connected at 20 with lever arm 19, composed of rods 19A and 19B. Each lever, while shown composed of two bars, can be made of a single bar if advisable. The lever arms taper outwardly from each end and are widest in the vicinity of pivot 20 to provide necessary strength with minimum weight.

A pair of links 21 and 22 are connected at their lower ends in a pivotable manner with the upper ends of the levers 18 and 19 such as by means of bolts 23 and 24. Each of the links 21 and 22 is shown composed of a pair of rods or bars. Link 21 is shown made of rods 21A and 21B while link 22 is made of rods 22A and 22B. Each link, while shown composed of two bars, can be made of a single bar if advisable. The upper ends of the links are pivotably connected by bolt 25.

The jaw body of each gripping member is shown pivotally connected to the lower ends of the lever arms. Gripping member 10 has jaw 14 pivotally connected to lever 18 by bolt 26 and jaw body 14A is pivotally connected to lever 19 by bolt 27. Each elongated rod extending upwardly from the jaw body is supported in a slidable manner by a guide means so the jaws of the lifting device are maintained parallel as they move toward and away from each other during movement of the device up and down. Elongated rod 16 extending from jaw 14 extends through a vertical hole in guide means 28 which is shown positioned to pivot about an axis common to the pivot at the intersection of lever arm 19 and link 21. FIGURE 4 shows, in an enlarged sectional view, rod 16 slidably located in guide means 28. The rod 16 passes through hole 30 to provide slidable action. Similarly, guide means 29 has a vertical hole in which rod 16A can slide up and down, to maintain movement of jaw 14A in a path parallel to jaw 14. Guide means 29 is also positioned to pivot about an axis common to bolt 24 and this is effected by bolt 24 joining together guide means 29 and the ends of lever arm 18 and link 22.

Gripping member 11 is like gripping member 10 and thus will not be described separately.

The face of each of the jaw bodies has a lower protruding lip, such as lip 35 on jaw body 14 and an elongated essentially vertical flat face 36 as shown most clearly in FIGURE 5. The lip 35 on each of the jaw bodies serves to firmly hold a slab being lifted by the device. In addition, the elongated flat face 36 maintains a group of slabs in a pile in a neatly positioned arrangement with respect to one another and serves to keep them from shifting to one side or the other during lifting and transporting. Lip 35 comprises in part a removable teeth carrying insert 50 which has a protruding horizontal flange 51 at the rear which fits into a mating slot in the jaw face. A series of bolts 52 removably holds the insert in place. Teeth 53 serve to further grip slabs lifted by the device.

Rigid spacer 12 is positioned so that each of its ends is located essentially at the pivotal intersection of the lever arms, such as bolt pivot 20 in gripping member 10. Spacer 12, as shown in FIGURES 8 and 9, is fabricated from two channel members 60 and 61 held fixedly apart by braces 62 and end plates 63. At each end of the spacer 12 are positioned pivot bolts for holding the actuating members. Thus, bolt 20 is at one end and holds actuating members 18 and 19. Collar 64 provides additional support for bolt 20. A pair of bolts 66 pass through spacer 12 and provide attachment means for cables 39 used to lift the whole lifting device when empty.

Each gripping member 10 and 11 has respectively a lifting eye 37 and 37A mounted pivotally to rotate on the same axis as the pivotal intersection of the links, such as links 21 and 22 on member 10 which pivot on bolt 25. Spacer 13 runs from lifting eyes 37 and 37A and serves, with spacer 12, to maintain gripping members 10 and 11

in spaced apart parallel relationship to one another. The spacers also restrict gripping members 10 and 11 to simultaneous identical movement. As shown in FIGURES 7 and 10, spacer 13 is made of two channel members 70 and 71 held in fixed apart position by a block 72 at each end. Cables 39 pass between the members 70 and 71. Each lifting eye 37 and 37A is shaped like an inverted U with the legs of the U held rigid by a bar 73 which pivots on a bolt such as 25.

10 Hook 42 serves to raise and lower the slab lifting device when it is empty. Cable 39 is purposely chosen to have only sufficient strength to safely handle the empty lifting device. Cable 39 has insufficient strength to support both the weight of the lifting device and a steel

15 slab to be transported in the jaws of the device. Since the jaws would not have a tight grip on a slab if lifting was tried by means of cable 39, this action is defeated by breaking of the cable before the slab can be moved. The actual lifting of a slab between the jaws of the lifting device is effected by means of heavy duty crane hooks placed in the openings 45 and 46 in eyes 37 and 37A. Only when lifting is effected through eyes 37 and 37A do the jaws of the device move together, in parallel arrangement, to grip a slab. The weight of the device in itself

20 initially causes the jaws to move together into gripping contact on a slab as the eyes 37 and 37A are lifted by a suitable crane. The weight of the slab exerts further force which causes each pair of opposing jaws to be forced into even tighter gripping action on the slab.

25 With reference to FIGURE 2, the lifting device has been transported by hook 42 to be positioned over slab 50. After the lifting device has been placed in position over the slab to be transported, lifting force is applied to eyes 37 and 37A thus causing the links and lever arms

30 to pivot about their connections and causing the jaws to move inwardly in parallel arrangement into contact with the slab. At this point cable 39 is in a relaxed or slack posture and all lifting is done through suitable hooking means placed through the eyes 37 and 37A.

35 FIGURES 1 to 3 and FIGURE 5 show how the protruding lip 35 at the end of the jaws permit lifting of a plurality of slabs on a pile even when upper slabs 81 are wider than the lowest slab 82 in the group being lifted. This assures firm, secure gripping.

40 The foregoing detailed description has been given for clearness of understanding only, and no unnecessary limitations should be understood therefrom, as modifications will be obvious to those skilled in the art.

45 What is claimed is:

1. A lifting device for metal slabs and the like comprising:
a pair of similar gripping members of the lazy tong type connected in parallel spaced apart relationship from each other by rigid spacers;
each gripping member having two opposing jaws and jaw actuating means which moves the jaws in-and-out in parallel relationship to one another;
each jaw having a jaw body and an elongated bar extending therefrom;
- 60 a pair of intersection pivotally connected lever arms pivotally connected at each lower end to a jaw body and at each upper end to the lower end of a pair of actuating links, the upper ends of the actuating links being pivotally joined together;
- 65 guide means, pivotally mounted on the gripping member, separately receiving each elongated bar through a hole therein; and
means operably associated with said actuating links to thereby simultaneously lift both gripping members whereby the weight of the lifting device and any load between the jaws forces opposing jaws inwardly toward each other.
- 70 2. A lifting device according to claim 1 in which a rigid spacer joins the opposing gripping members at the intersecting pivot of the lever arms, and another spacer joins

the opposing gripping members at the connecting pivot of the upper ends of the actuating links.

3. A lifting device according to claim 1 in which the pivot for the guide means, and the pivotal connection of the lever arms with the links, have a common axis.

4. A lifting device according to claim 1 in which each lever arm, and each actuating link, comprises at least two spaced apart rods.

5. A lifting device for metal slabs and the like comprising:

a pair of similar gripping members of the lazy tong type connected in parallel spaced apart relationship from each other by rigid spacers; each gripping member having two opposing jaws and jaw actuating means which moves the jaws in-and-out in parallel relationship to one another;

each jaw having a jaw body and an elongated bar extending therefrom;

a pair of intersecting pivotally connected lever arms pivotally connected at each lower end to a jaw body and at each upper end to the lower end of a pair of actuating links, the upper ends of the actuating links being pivotally joined together;

each lever arm and each actuating link comprising at least two spaced apart rods;

one of said rigid spacers joining opposing gripping members at the intersecting pivot of the lever arms, and

another rigid spacer joining the opposing gripping members at the connecting pivot of the upper ends of the actuating links;

guide means mounted on the gripping member and pivoting about an axis common to the connecting pivot of the lever arm intersecting with the actuating links, said guide means separately receiving the elongated bar extending from the jaw through a hole therein; and

means operably associated with said actuating links to thereby simultaneously lift both gripping members whereby the weight of the lifting device and any load between the jaws forces opposing jaws inwardly toward each other.
